UNITED STATES PATENT OFFICE.

GEORGE BEATTY, ROBERT J. BEATTY, AND GEORGE W. DAVIS, OF STEUBENVILLE, OHIO.

DESIGN FOR GLASSWARE.

SPECIFICATION forming part of Design No. 16,371, dated November 10, 1885.

Application filed August 13, 1885. Serial No. 174,342. Term of patent 7 years.

To all whom it may concern:

Be it known that we, GEORGE BEATTY, ROBERT J. BEATTY, and GEORGE W. DAVIS, residing at Steubenville, in the county of Jefferson and State of Ohio, citizens of the United States, have invented or discovered a certain new and original Design for Glassware, of which design the following is a specification.

10 In the accompanying drawing, which makes part of this specification, the figure is a view in side elevation of a glass vessel having its outer surface ornamented by our new and original design.

15 The leading features of our design consist of what is termed in the art "hob-nail" diamonds 1, stars 2, and semi-cylindrical elevations 3, the latter being set at an angle to each other in **V** form. The semi-cylindrical elevations 3 are set at an angle to each other around the upper and lower edges of the vessel at any desired distance apart. Between and

set the stars 2 in any desired order, and between the points of adjacent stars are located 25 the hob-nail diamonds 1, as shown.

In the case of glass vessels consisting of two parts, as shown, the apices of the semi-cylindrical elevations point downward, while in the body of the vessel the apices will point 30 upward.

We claim herein as our invention—

A design for the ornamentation of glassware, the same consisting of semi-cylindrical elevations 3, set at an angle to each other in **V** form, 35 with hob-nail diamonds and stars set about and between the limbs of the same, as shown and described.

In testimony whereof we have hereunto set our hands.

GEORGE BEATTY.
ROBERT J. BEATTY.
GEORGE W. DAVIS.
